BUTTON HOLDER AND BUTTON

Roman Frydrychowicz, 5273 Taunton St., Vancouver,
British Columbia, Canada

Filed June 11, 1957, Ser. No. 664,933

1 Claim. (Cl. 24—107)

This invention relates generally to buttons for garments, and more particularly has reference to a button holder that is adapted for supporting upon the garment a conventional button, without the necessity of attaching the button by means of thread. The invention further has reference to a novelly designed button which can be engaged with the button holder, should one prefer not to use a conventional button in association with the holder.

It is well known that sewing buttons on garments is a tedious, time-consuming task. This duty requires a certain amount of skill and patience that may not be possessed by one confronted with the necessity of attaching the button to a garment.

Not only is the conventional method of attaching a button to a garment tedious and time-consuming, but also, once the button is attached, it must thereafter remain on the garment more or less permanently. Thus, it must pass through clothes laundering machines, be left on the garment while the garment is being pressed or ironed, etc. This is undesirable, in many instances. Hence, there is a clear need, recognized to some extent in the prior art, for quickly attachable and detachable buttons. Such buttons should be attachable without the use of needle and thread, by unskilled persons.

So-called "threadless" buttons have heretofore been conceived. However, in some instances, the buttons have been so designed as to permit them to be removed from the garment only by a force that tends to damage the button. Such a button must appropriately be considered, thus, as a single-use button.

In the same or other instances, the buttons which have previously been designed have been such as to produce spots of rusts after laundering of the garment if the button is not removed. This has militated against the commercial success of the devices, in view of the fact that the buttons cannot be removed readily. In still other button constructions of which I have knowledge, the garment must be specially apertured to receive the buttons.

The main object of the present invention is to provide a generally improved, quickly attachable button that will not have the deficiencies noted in prior art constructions.

Among more particular objects of the invention, there are, among others, the following:

To provide a button that will be adapted to be used on garments of any type, having different thicknesses of fabric, with the button in every instance being adapted for swift attachment to or detachment from the garment.

To provide a button holder that can be used with wholly conventional buttons, either of the two-hole or four-hole type;

To form the holder in a manner such that it will not injure the garment to which it is attached;

To permit the detachment of the button to be carried out with a facility matching that of the attachment of the button to the garment;

To provide a button which will itself be designed for use with the button holder formed in accordance with the present invention, thus permitting either a conventional button, or alternatively a button according to the invention, to be used with the button holder;

To facilitate separation of the several components of

2

the button holder from one another and from the fabric to which they are attached, whenever such separation is desired, while at the same time insuring that said components will remain assembled with one another and with the fabric of the garment at all times; and

To so design the button as to permit the same to be made in any of various sizes, shapes, colors, and materials.

These together with other objects and advantages which will become subsequently apparent reside in the details of construction and operation as more fully hereinafter described and claimed, reference being had to the accompanying drawings forming a part thereof, wherein like numerals refer to like parts throughout and in which:

15 Figure 1 is a front elevational view of a button holder according to the present invention illustrated in supporting relation to a conventional button, a piece of fabric on which the button and button holder are mounted being shown fragmentarily;

20 Figure 2 is a sectional view diametrically through the button holder and button, substantially on line 2—2 of Figure 1;

Figure 3 is an exploded perspective view of the button holder and of a conventional button with which it is associated; and

25 Figure 4 is a side elevational view of a button formed according to the present invention and adapted for use with the button holder.

Referring to the drawings in detail, designated generally at 10 is a conventional button. The shapes, sizes, and thicknesses of conventional buttons are many, of course. Therefore, that shown is purely illustrative of one of many conventional buttons with which the invention may be used.

30 35 The button is shown in position upon a piece of fabric 12 which may comprise part of a garment, such as a coat, shirt, etc.

The button, as is usual, has a centrally located series of apertures 14. In the illustrated example the button 40 has four rectangularly spaced apertures. Some buttons are provided with only two apertures. As will presently appear, the button holder constituting the present invention can be used with either type of button.

In accordance with the invention, a button retainer element 16, having a flat, disc-like form in the illustrated example, is provided with a plurality of thin, elongated straight prongs 18 of springable material. At their inner ends the prongs are embedded in, or otherwise fixedly secured to the inner surface of the element 16. At their outer ends, the prongs 18 are provided with elongated, pointed barbs 20. The barbs 20 are defined through the provision of laterally opening, angular notches 21, formed in the side surfaces of the prongs 18. The notches 21 are so designed as to have the walls thereof disposed at not less than a 90° angle to each other. The outer wall, that is, the wall disposed adjacent the sloped surface of the barb 20, is at an obtuse angle to the length of the prong. The purpose of this arrangement will be presently made clearly apparent.

45 50 55 Between the button 10 and the fabric 12 there is provided a spacer disc 22. This has openings 24 registering with those of the button 10. The spacer disc 22 is used in instances in which the button is to be spaced outwardly from the fabric 12. In some instances, the button need not be spaced outwardly from the fabric in this way, in which event the spacer disc may be eliminated. Or, the particular shape of the button may be such as to make unnecessary a spacer disc. This would be true, for example, when the button is of a shape such that its inner surface is convexly formed, so as to space the periphery of the button away from the fabric.

60 65 70 An inner retainer member 26 is formed as a concavo-

convex shell, having a retaining flange extending continuously at its periphery and designated at 27. The retaining flange receives a flat retaining plate 28 having a large center opening 30. The opening is formed with an undercut or frustoconical wall, that tapers in the direction of the cavity or space 31 defined between the retainer plate 28 and the body portion of the retainer member 26.

The plate 28 is secured permanently within the retainer member 26 by peening over the edge of the flange 27, upon the circumference of the retainer plate, as shown at 33 in Figure 2.

In use of the button holder shown in Figures 1-3, a conventional button of any desired size or shape is positioned over the fabric. A spacer plate can be employed in association therewith if necessary. The prongs 18 are extended through the openings 14, 24, and are then shifted easily through the fabric 12. At the inner side the prongs are extended into the opening 30 and initially will be cammingly engaged by the sloped wall of the opening. Thus, the free ends of the prongs are all temporarily forced inwardly toward each other. As the prongs continue their movement into the space 31, eventually the angular notches 21 will be brought into registration with the inner face of the retaining plate 28. As a result, the barbs engage over the edge of the wall 30. This is shown to particular advantage in Figure 2. It will be apparent that the arrangement results in the button 10 and spacer 22 being clamped, together with the fabric 12, between the outer and inner retainer members 16, 26 respectively.

Thereafter, the button can be used in the regular manner. It will be seen that any lateral pressures exerted on the button, or on any component of the button holder, will have no effect in respect to separating the component parts of the assembly.

If, however, it is desired to remove the button, one need only insert a blade-like element, not shown, between the outer retainer member 16 and the button 10. Thereafter, the retainer member 16 can be shifted by a prying action axially outwardly from the inner retainer member. The previously mentioned sloping of the end walls of the notches 21 permits the barbs of the prongs to be cammingly biased inwardly to disengage the plate 28. It is for this reason that the end walls of the notches 21 are at an obtuse angle relative to the lengths of the prongs.

Thus, it is observed that the button can be attached to or detached from a garment with maximum ease and speed. In every instance, the garment will not be damaged by use of the button. Further, the button is capable of reuse any desired number of times. Still further, since the spacing of openings 14 of a conventional button remains substantially the same in all buttons or at least in a large percentage of conventional buttons, the button holder can be used with buttons 10 that may vary widely from one another in respect to size, shape, etc.

In Figure 4 there is illustrated a button which can be used in place of the conventional button 10. When the button of Figure 4 is used, the button retainer 16 is not employed. Instead, the disc-like member 32 itself constitutes a button as well as a retainer member.

The disc-like retainer member 32 can of course be of any desired shape, thickness or size. This being so, the necessity for making the same as inconspicuous as possible (which necessity is present in respect to the retainer member 16) does not exist. The retainer member 32 can therefore be comparatively thick. In view of this, the prong means can be readily embedded in the same and can comprise a single piece of stout, slightly springable rod material embedded in the inner face of the member 32. The member 32 on its inner face is formed, in the illustrated example, with a boss 34 constituting a spacer. The prong means includes a wire having legs 36 defining prongs. The legs are connected by a bight 38 embedded

in the member 32. On their outer ends, prongs 36 have barbs defined by notches 40, the same as in the first form of the invention.

It will be thus apparent that the device has considerable versatility in respect to the use thereof and can be attached to and detached readily from the garment. Still further, the button holder can be used either with a conventional button or with a button such as shown in Figure 4. Then again, the button holder can be used with conventional buttons of various sizes and shapes. Still further, the device is so formed that the parts resist separation under the influence of lateral pressures, but can be readily pulled apart by an axial, prying action such as previously described herein. The retainer 16 can be formed either with two or four prongs since conventional buttons such as button 10 are always formed with two or four openings. The button in Figure 4, however, can be formed with two, three, or four prongs, as desired.

Of course, the spacer 22 can be of any desired thickness, or a plurality of spacers can be employed, according to the needs of the particular situation, which would be governed by the thickness of the particular fabric on which the button is mounted.

Considering Figure 4, the prong means may be used exclusively of the retainer member 32 to retain a conventional button in place. The prong means may take on the configuration of a staple and be suitably colored to conform to the color of a button with which it will be used and inserted by means of a suitable staple gun or the like.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

A separable button construction comprising; a generally planiform, disc-like, outer member to be disposed at one side of a piece of fabric; a plurality of spaced, prongs extending substantially normal from said member and having barbs for penetrating the fabric and be disposed on the other side thereof, juxtapositionable button and spacer elements having aligned apertures through which said prongs extend with said outer member overlying said button element, said prongs being of a spring material; and a hollow retainer positionable at the other side of said fabric and including a transverse plate having a center opening through which said prongs will extend, said plate including a tapered edge defining said center opening, said prongs having angular notches at the bases of said barbs defined by intersecting straight walls and tapered edge therein to yieldably retain the button assembled, the walls of said notches being at an angle of not less than 90 degrees to each other, the one wall of each notch closest to the free end of the prongs being disposed obliquely relative to the length of the prongs to cam said prongs inwardly upon relative axial movement of the prongs with respect to said retainer during separation of the same.
